UNITED STATES PATENT OFFICE.

JOHN HARVEY KELLOGG, OF BATTLE CREEK, MICHIGAN.

MOVEMENT-CURE APPARATUS.

No. 835,622.

Specification of Letters Patent.

Patented Nov. 13, 1906.

Application filed September 5, 1905. Serial No. 277,081.

To all whom it may concern:

Be it known that I, JOHN HARVEY KELLOGG, a citizen of the United States, residing at Battle Creek, in the county of Calhoun, State of Michigan, have invented certain new and useful Improvements in Movement-Cure Apparatus, of which the following is a specification.

This invention relates to improvements in a movement-cure apparatus.

The objects of this invention are, first, to provide an improved movement-cure apparatus by which a vibratory or shaking movement may be imparted to the whole body; second, to provide an improved movement-cure apparatus by which the force of the vibrations are under the perfect control of the user or operator.

Further objects and objects relating to the structural details will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawings, forming a part of this specification, in which—

Figure 1 is a side elevation view of my improved movement-cure apparatus. Fig. 2 is a detail sectional view taken on a line corresponding to line 2 2 of Fig. 3, showing the relation of the parts. Fig. 3 is a detail sectional view taken on a line 3 3 of Fig. 2.

In the drawings similar letters of reference refer to similar parts throughout the several views, and the sectional views are taken looking in the direction of the little arrows at the ends of the section-lines.

Referring to the drawings, the base A is supported by feet a, of rubber or other suitable resilient material. These feet rest in sockets a', which are secured to the floor. A body rest or support, preferably comprising a pair of oppositely-facing chairs having common side rails B and a common back B', is arranged upon the base A. A pair of shaft-hangers C are secured upon the side rails B at a central point, preferably beneath the back B'. A shaft, made up of sections D and D' and the hollow drum or wheel D'', by which the sections are connected, is sup-

ported by the hangers C. The wheel or drum D'' is preferably made up of sections screw-threaded together, a section being secured to each shaft-section. A weight e' is arranged within the drum D''. This weight throws the shaft, out of balance so that as it is revolved it is caused to vibrate and through its bearings impart its vibrations to the body rest or support. The weight is adjusted in the drum by means of the screw E, which is connected thereto by the chain e. The screw E projects into the shaft-section D', which is made hollow to receive it. On the outer end of the screw E is a hand-wheel E' for convenience in adjustment. The screw is supported by the threaded block E'' on one of the side rails B'. By means of this screw the weight is thrown in or out from the shaft, thereby controlling the force of the vibrations. Guides e'', in which the weight e' moves in and out, are arranged within the drum.

The shaft is preferably driven from the motor F, which is located beneath the seats. The motor is connected to the shaft by means of a suitable belt, as f, which is arranged on the grooved pulley D''' thereon. As stated, the weight e' throws the shaft out of balance, so that as the shaft revolves it vibrates and being mounted in bearings carried by the seats imparts its vibration thereto. By the adjustment of the weights the force of the vibrations is controlled. By the particular arrangement illustrated and described the vibrations may be controlled to a nicety, and this may be done while the apparatus is in operation.

I have illustrated and described my improved movement-cure apparatus in detail in the form preferred by me on account of its structural simplicity and convenience of operation, although I am aware that it is capable of considerable variation in structural details without departing from my invention.

Having thus described my invention, what I claim as new, and desire to secure by Letters Patent, is—

1. In a movement-cure apparatus, the combination of a base; resilient feet for said base; a seat arranged on said base; a shaft made up of sections, one of which is hollow; a hollow wheel or drum connecting said shaft-sections; bearings for said shaft, carried by said seat; a weight arranged in said drum; a

radial guide in said drum for said weight; a screw projecting into the hollow section of said shaft; and a cable connecting said weight to said screw, for the purpose specified.

5. 2. In a movement-cure apparatus, the combination of a base; a seat arranged on said base; a shaft made up of sections, one of which is hollow; a hollow wheel or drum connecting said shaft-sections; bearings for said shaft, carried by said seat; a weight arranged in said drum; a radial guide in said drum for said weight; a screw projecting into the hollow section of said shaft; and a cable connecting said weight to said screw, for the purpose specified.

10. 3. In a movement-cure apparatus, the combination of a base; resilient feet for said base; a seat arranged on said base; a shaft made up of sections, one of which is hollow; a hollow wheel or drum connecting said shaft-sections; bearings for said shaft, carried by said seat; a weight arranged in said drum; a radial guide in said drum for said weight; and means for adjusting said weight, for the purpose specified.

15. 4. In a movement-cure apparatus, the combination of a base; a seat arranged on said base; a shaft; a hollow wheel or drum carried by said shaft; bearings for said shaft, carried by said seat; a weight arranged in said drum; a radial guide in said drum for said weight; and means for adjusting said weight, for the purpose specified.

20. 5. In a movement-cure apparatus, the combination of a base; resilient feet for said base; a seat arranged on said base; a shaft; a hollow wheel or drum carried by said shaft; bearings for said shaft, carried by said seat; a weight arranged in said drum, for the purpose specified.

25. 6. In a movement-cure apparatus, the combination of a base; a seat arranged on said base; a shaft; a hollow wheel or drum carried by said shaft; bearings for said shaft, carried by said seat; and a weight arranged in said drum, for the purpose specified.

30. 7. In a movement-cure apparatus, the combination of a base; resilient feet for said base; a seat arranged on said base; a shaft; bearings for said shaft, carried by said seat; a weight carried by said shaft; and means for adjusting said weight to and from the said shaft, for the purpose specified.

35. 8. In a movement-cure apparatus, the combination of a base; a seat arranged on said base; a shaft; bearings for said shaft, carried by said weight; a weight carried by said shaft; and means for adjusting said weight to and from the said shaft, for the purpose specified.

40. 9. In a movement-cure apparatus, the combination of a body rest or support; resilient feet therefor; a shaft made up of sections, one of which is hollow; bearings for

said shaft, carried by said body rest or support; a weight arranged in said drum; a radial guide in said drum for said weight; a screw projecting into the hollow section of said shaft; and a cable connecting said weight to said screw, for the purpose specified.

45. 10. In a movement-cure apparatus, the combination of a body rest or support; a shaft made up of sections, one of which is hollow; a hollow wheel or drum connecting said shaft-sections; bearings for said shaft, carried by said body rest or support; a weight arranged in said drum; a radial guide in said drum for said weight; a screw projecting into the hollow section of said shaft; and a cable connecting said weight to said screw, for the purpose specified.

50. 11. In a movement-cure apparatus, the combination of a body rest or support; resilient feet therefor; a shaft; a hollow wheel or drum carried by said shaft; bearings for said shaft, carried by said body rest or support; a weight arranged in said drum; a radial guide in said drum for said weight; and means for adjusting said weight, for the purpose specified.

55. 12. In a movement-cure apparatus, the combination of a body rest or support; a shaft; a hollow wheel or drum carried by said shaft; bearings for said shaft, carried by said body rest or support; a weight arranged in said drum; a radial guide in said drum for said weight; and means for adjusting said weight, for the purpose specified.

60. 13. In a movement-cure apparatus, the combination of a body rest or support; resilient feet therefor; a shaft; a hollow wheel or drum carried by said shaft; bearings for said shaft, carried by said body rest or support; a weight arranged in said drum; for the purpose specified.

65. 14. In a movement-cure apparatus, the combination of a body rest or support; a shaft; a hollow wheel or drum carried by said shaft; bearings for said shaft, carried by said body rest or support; and a weight arranged in said drum, for the purpose specified.

70. 15. In a movement-cure apparatus, the combination of a seat or chair; resilient feet for said seat or chair; a shaft; bearings therefor, supported by said chair; a weight adjustably mounted on said shaft; and means for adjusting said weight, for the purpose specified.

75. 16. In a movement-cure apparatus, the combination of a seat or chair; resilient feet for said seat or chair; a shaft; bearings therefor, supported by said chair; a weight mounted on said shaft; and means for adjusting said weight, for the purpose specified.

80. 17. In a movement-cure apparatus, the

combination of a body rest or support; resilient feet for said body rest or support; a shaft; bearings therefor, supported by said body rest or support; a weight adjustably mounted on said shaft; and means for adjusting said weight, for the purpose specified.

5 In witness whereof I have hereunto set my

hand and seal in the presence of two witnesses.
